CLAIM

The ornamental design for a river tube with canopy, as shown and described.

DESCRIPTION

FIG. 1 is a perspective view of a river tube with canopy showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof; and,

FIG. 9 is a partial enlarged view of portion 9 in FIG. 2.

The evenly broken line showing of the river tube with canopy is for the purpose of illustrating portions of the article that forms no part of the claimed design. The dot-dash that demarcate claimed areas in FIGS. 2&9 have been included to show enlargement for clarity. The lines themselves do not form part of the claimed design.
